(57) **CLAIM**

The ornamental design for a reader device case, as shown and described.

DESCRIPTION

FIG. 1 illustrates a top view for a reader device case.

FIG. 2 illustrates a bottom view for the reader device case.

FIG. 3 illustrates a front view for the reader device case.

FIG. 4 illustrates a side view for the reader device case.

FIG. 5 illustrates a side view for the reader device case.

FIG. 6 illustrates a back view for the reader device case.

FIG. 7 illustrates a perspective back view for the reader device case.

FIG. 8 illustrates a perspective front view for the reader device case.

FIG. 9 illustrates a perspective back view for the reader device case.

FIG. 10 illustrates a perspective back view for the reader device case.

FIG. 11 illustrates a perspective front view for the reader device case; and,

FIG. 12 illustrates a perspective front view for the reader device case.

The broken lines depict portions of the reader device case that form no part of the claimed design.
